FISH LURE

Frank A. Serafin, Pontiac, Mich.

Application December 13, 1954, Serial No. 33,511

Term of patent 14 years

(Cl. D31—4)

Fig. 1 is a side elevational view of the fish lure embodying my new design showing the attaching rings, swivel, and hooks, in dotted lines;

Fig. 2 is a top plan view of Fig. 1;

Fig. 3 is a cross-sectional view of the Fig. 1 taken on line 3—3 thereof; and

Fig. 4 is a cross-sectional view of Fig. 1 taken on the line 4—4 thereof.

The characteristic features of my design reside in the portions shown in solid lines.

I claim:

The ornamental design for a fish lure, as shown and described.
